US0D1068335S

(12) United States Design Patent (10) Patent No.: US D1,068,335 S
(45) Date of Patent: * Apr. 1, 2025

(54) MATTRESS COVER

(71) Applicant: Sealy Technology LLC, Trinity, NC (US)

(72) Inventors: Melissa McCourtie, Greensboro, NC (US); Fernanda Garcia, Puebla (MX)

(73) Assignee: SEALY TECHNOLOGY LLC, Trinity, NC (US)

() Term: 15 Years

(21) Appl. No.: 29/870,323

(22) Filed: Jan. 20, 2023

(51) LOC (15) Cl. 06-13

(52) U.S. Cl. USPC D6/606

(58) Field of Classification Search

USPC D6/595-602, 604-605, 610-611
CPC A47C 23/00; A47C 27/00; A47C 27/002;
